UNITED STATES PATENT OFFICE.

CHARLES L. LOVERCHECK, OF BROOKLYN, NEW YORK, ASSIGNOR, BY MESNE ASSIGNMENTS, TO GEORGE SAGUE MFG. CORP., OF POUGHKEEPSIE, NEW YORK, A CORPORATION OF NEW YORK.

ENVELOPE AND LIKE FEED MECHANISM.

Application filed September 18, 1920. Serial No. 411,095.

To all whom it may concern:

Be it known that I, CHARLES L. LOVERCHECK, a citizen of the United States, residing in Brooklyn, in the county of Kings and State of New York, have invented certain new and useful Improvements in Envelope and like Feed Mechanism, of which the following is a specification.

This invention relates in general to means for successively feeding articles such as envelopes, folded circulars, sheets of paper or the like, from a magazine or pile of such articles.

The invention finds particular adaption for use as the envelope feeding mechanism magazine and also as the circular feeding mechanisms and magazines of envelope filling machines similar to the one disclosed in the U. S. Patent No. 1,317,387, of September 30, 1919 to Penney, Whiteman and Russ, in which the envelopes are successively fed to a certain position and in turn articles such as circulars or the like, are successively fed into such envelopes.

One object of the invention is to provide means for effectively discharging the envelopes or circulars one at a time from the bottom of a magazine and feeding them forward at certain predetermined intervals of time, and properly positioning them as to time and position for proper subsequent co-operation.

Particular features of the invention are the provision of a feeding throat or passage having retarding members whereby the articles such as envelopes, circulars, sheets of paper or the like, may be successively fed forward one at a time and prevented in an effective manner from passing in larger numbers.

Another object of the invention is to provide a magazine wherein the pressure of the pile of articles in the magazine is sufficiently relieved from the lowermost article to permit the easy withdrawal of the latter by the feeding means.

Another object of the invention is to provide a magazine adjustable to different sizes of articles.

Another object is to provide a magazine so formed that it and the articles co-act to assist the ejection of the articles by the feeding means.

These and other objects of the invention

will appear as the description proceeds; and while herein minute details of the invention are disclosed, the invention is not limited to these, since many and various changes may be made without departing from the spirit of the invention or exceeding the scope of the appended claims.

In the accompanying drawings, showing by way of example, one of many possible embodiments of the invention,

Figure 1 is a side elevation of the feed mechanism and magazine, showing a pile of envelopes, circulars, or the like ready to be discharged;

Fig. 2 is a plan of the same;

Fig. 3 is a fragmental inner end view showing more in detail the retarding members forming the throat of the feed mechanism.

Reference to said patent will show magazine and feed mechanisms for envelopes to be filled and for circulars to be inserted in the envelope. The magazine and feed mechanism herein shown and described is intended for use for both of these purposes, but it is of course understood that its use is no way limited to machines of the class shown in the patents, or even to the feeding of paper articles.

The improved magazine and feed mechanism is shown in combination with the machine frame 10 on which is mounted a horizontally disposed T-shaped supporting bracket 11 supported at its joining portion on a pedestal 12, (Fig. 1) mounted on said frame 10. Longitudinal adjusting slots 15 and 16 (Fig. 2) are provided in the free ends of the cross bars 17 and in the rearwardly pointing main bar 18.

A pair of side supports each comprising, forward and rear arms 21 and 22 is provided with a boss 23 (Fig. 1) resting on said cross bars 17 and formed with an elongated slide lug 24 slidably and non-rotatably engaged in said slots 15 of the side bars. Said boss is provided with a threaded bore passing therethrough and receiving a clamping bolt 25 screwed therein having a milled head engaging the cross bar thereby adjustably securing the boss 23 and side supports in place.

Upright forward and rear side fingers 26 and 27 carried on the respective ends of said arms 21 and 22 are adapted to engage the

side edges of the envelopes, circulars or other articles 30 disposed in a pile therebetween.

An upright bracket 31 adjustably clamped on the rear part of said main bar by means of a clamping screw 32 engaging in said slot 16 is provided with a vertical slot 34 in its upper part in which engages a lug of an adjustable block 35 disposed on the inner face of said upright bracket and provided with a threaded bore in which is received a clamping bolt 36 having its head engaging the rear face of said bracket and clamping the side block in place.

15 An inverted U-shaped rear support 38 comprising side members 39 is secured to the inner face of said slide block, and said members have their lower part downwardly and forwardly and then downwardly inclined to give support with a forwardly camming action to the articles near the bottom of said pile, and to form a slight hump 40 joining the slanting or camming part 41 and the lower vertical part of the side members, 20 below which hump the rear edge of the several lowest articles 42, 43 and 44, may fall when they are drawn forwardly, as will be explained, thereby spacing the rear and intermediate part of said lowest articles from 25 the pile as shown in Fig. 1. The camming part 41 also assists in the forward movement of the articles.

At the discharge or forward end of the magazine a head bracket 45 (Fig. 2) and a rail bracket 46 are mounted on said frame 10 and provided at the upper part with aligned bearing openings, in which opening of the head bracket is received a short drive shaft 47 having a head 48 on its inner end, 30 and carrying a pinion 50 fast thereon near the outer end, and a collar 51 loosely received on the shaft and disposed against the outer face of said pinion.

A reciprocating link 52, reciprocated by a crank, eccentric, cam or other suitable means carried on the frame 10, is provided with a longitudinal slot 53 slidably received on said collar 51 next to said pinion and held in place by a washer 54 secured in place on the outer end of the shaft by a screw 55. A 35 rack 57 on said link engages said pinion, whereby when the link is reciprocated, the pinion 50 and shaft 47 are rotated backward and forward.

55 A ratchet wheel 59 fast on said shaft 47 near the inner end thereof is yieldably engaged by a pawl 60 pivotally mounted on the outer face of a driving face plate 61 loosely received on said shaft and provided with an eccentrically disposed drive pin 62, and a centering boss 63 engaging against said head 48.

Said pawl is yieldably pressed against said ratchet by means of a coil spring 65 disposed around a screw 66 on said face

plate, and rotates said drive face plate forwardly when the shaft is rotated forwardly and permits the plate to remain at rest when the shaft and ratchet are rotated backwardly, whereby an intermittent forward 70 rotation is given said face plate.

A driven face plate 68 is received on said boss 63, and is itself provided with a hub 69 at its exposed face, and with an opening 75 receiving said pin 62.

A dead spindle 75 adjustably received in said bearing opening of the tail stock 46 is provided with an adjusting milled head 76 at its outer end, and is held fixed in adjusted position by a set screw 77.

An intermediately squared supporting shaft 80 disposed near said forward fingers 26 and above said forward arms 21, has one end joining or fast in said hub 69 and the other end provided with a bearing bore 81 receiving the reduced inner end 82 of the spindle 75. Said squared shaft carries a soft rubber cylindrical feed roller 84 mounted on said squared portion and adapted to engage and support the said lowest article 90 42 near its forward end, thereby to project the said lowest article forwardly, when said ratchet is rotated forwardly as previously explained.

On said frame 10 forward of said roller 84 is mounted a standard 87. On this standard is soldered a horizontally disposed U-shaped guide 88 secured on the top face of said standard and having its side members 89 perpendicular to and pointing forwardly away from the vertical plane of the axis of said roller.

An arch-shaped bracket 90 adjustably mounted on the top face of said bearing brackets 45 and 46 is provided with a slot 100 91 (Fig. 1) above and axially parallel to said U-shaped guide and adjustably receiving a lug 92 on which is mounted a supporting piece 93. A clamping screw 94 is received in said lug and provided with a milled head engaging said bracket 90 and holding the piece 93 in place. The lug 92 and piece 93 are exactly positioned and adjusted by a set screw 95. A U-shaped bracket 96 secured to the rear end face of 110 said piece has its side members provided in their lower ends with slots 97 in which are secured a downwardly and forwardly disposed tongue 98 having its upper end secured in said slots and its lower end 99 120 (Fig. 3) disposed between said side members 89 approximately midway of the guide and slightly below the level of the top face of the guide to form therewith a gate or throat device. When the lowest article 42 is ejected by the roll 84 it is projected under the tip of said tongue, thereby to depress the portion of the article between said side members, thus warping the article thereby 125 raising the lateral portions of the article 130

165

- and thereby holding the next to the bottom article raised against the tongue to prevent its ejection. When the support 39 and bracket 31 are properly adjusted, the lower 5 part of said tongue 98 is far enough from said hump 41 to permit only a few of the lowest articles 42, 43 and 44 to fall below the hump, as shown in Fig. 1, the other articles being held up by the hump.
- 10 The operation of the feed mechanism will be readily understood from the foregoing and need now be only briefly summarized as follows:
- 15 The pile of envelopes, circulars or other articles 30 is placed in the magazine as shown in Fig. 1, the fingers 26 and 27 and the rear support 39 being adjusted to the size of the articles by manipulating the screws 25, 32 and 36. Proper adjustment of 20 the support 39 will enable the support to exert a forwardly camming action to the articles near the bottom of said pile, thereby to assist in their forward movement against the lower part of the tongue 98, so 25 that the several lowest 42, 43 and 44 articles may fall below the hump 41, thereby spacing the rear and intermediate part of said lowest articles from the pile, thus reducing 30 the contact of the articles with each other and reducing the contact of the lowest article to that part thereof just above the roller 84, thereby reducing the friction to a minimum.
- 35 Each time an article is to be fed, the link 32 is moved in the direction of the right hand arrow of Fig. 2, thereby rotating the roll 84, which frictionally engages and drags forward the lowest article and projects it beneath the lower end of the tongue 98 thereby bringing the mid part of the front 40 edge of the article between said side members 89 and slightly below the level of the top face of the guide, thereby raising the lateral portions of the article (Fig. 3) thereby 45 to hold the next to the bottom article 43 raised from the tip of the tongue to prevent egress of the articles 43, which with the articles above it have been cammed forward to contact with the tongue by the camming part 50 41 and the friction of the article beneath.
- 55 The rotary movement of the roll 84 continues until the article is entirely ejected, whereupon the article is further operated upon by said machine. During this operation by the machine, the link 52 is moved in the direction of the left hand arrow, while the roll 84 remains at rest, thereby preparing the mechanism to eject the next article.
- 60 I claim as my invention:
1. In combination, a magazine for holding a pile of flat articles and comprising a rear support; a rotary feed roll at the forward end of said magazine; a guide comprising members forward of the roll; and a
- downwardly and forwardly pointing tongue against which the articles are forced by said roll and having its lower end disposed between said side members; said rear support having its lower part formed to give a forwardly camming action to the articles near the bottom of said pile and to form a slight hump below which the rear edge of the several lowest articles may fall when they are drawn forwardly by said feed roll thereby spacing the rear and intermediate part of said lowest articles from the pile; the lower part of said tongue being far enough from said hump to permit only a few of the lowest articles to fall below the hump, the intermediate part of the tongue holding the intermediate articles from falling below the hump. 70
2. In combination, a feed means; and a throat device adapted to depress a portion 75 and to raise the other portions of the lowest article of a pile, thereby to raise the next lowest article to prevent its ejection through the throat device.
3. In combination, a feed means; and a 80 device adapted to raise the portions of the lowest article of a pile thereby to raise the next lowest article to prevent its ejection.
4. In combination, a feed means for feeding from a pile of articles; and a throat device adapted when the lowest articles is 85 ejected to depress a portion thereof and to raise lateral portions thereof, thereby to raise the next lowest article to prevent its ejection. 90
5. In combination, a feed means; side-members forward of said means; and a device having its lower end disposed between said side members whereby, when a flat article is ejected, the portion thereof between said members will be depressed, thereby to raise the lateral portions of the lowest article, thereby to raise the next lowest article to prevent its ejection. 95
6. In combination, a magazine, a feed 100 means at the discharge end of said magazine; parallel side members secured forward of said means; and a downwardly and forwardly disposed tongue having its lower end disposed between said side members approximately midway of the guide and slightly below the level of the top face thereof, whereby, when the article is ejected by the feed means it will project said lowest article under the tip of said tongue and depress the portion of the article between said side members, thereby to raise the lateral portions of the article thereby to hold the next to the bottom article raised against the tongue to prevent its ejection. 110
7. In combination, a magazine; a feed 115 means at the discharge end of said magazine, and on which the discharge end of the lowest of a pile of articles in the magazine rests; a horizontal guide secured forward of said 120
- 65 125
- 80 130

- means and having side members pointing forwardly from said means; and a downwardly and forwardly disposed tongue having its lower end disposed between said side members approximately midway of the 5 guide and slightly below the level of the top face of the guide, whereby, when the article is ejected by the feed means, to project said lowest article under the tip of said tongue 10 and to depress the portion of the article between said side members, thereby to raise the lateral portions of the article thereby to hold the next to the bottom article raised against the tongue to prevent its ejection.
- 15 8. In combination, a magazine for holding a pile of flat articles; a short shaft at the discharge end of said magazine and having a head on its inner end; a dead spindle alined with said shaft; a supporting shaft 20 having one end supported and rotated by said short shaft; and the other end provided with a bearing bore receiving said spindle; a soft rubber cylindrical feed roll fast on said supporting shaft and adapted 25 to engage and support the forward end of the lowest of said articles, and to project said lowest article forwardly when said roll is rotated forwardly; and a throat forward of the roll.
- 30 9. In combination, a magazine for holding a pile of flat articles; a head bracket and a tail bracket at the discharge end of said magazine and provided at the upper part with alined bearing openings; a short shaft 35 in said opening of the head bracket and having a head on its inner end; a drive face plate received on said shaft against said ratchet and provided with an eccentric drive pin, and a boss engaging against said head; a driven face plate received on said 40 sleeve boss, and itself provided with a hub at its exposed face, and an eccentric opening receiving said pin; a dead spindle adjustably received in said tail stock; an intermediately squared supporting shaft having 45 one end joining said hub and the other end provided with a bearing bore receiving said spindle; a soft rubber cylindrical feed roll mounted on the squared portion of the shaft. 50 and adapted to engage and support the forward end of the lowest of said articles, and to project said lowest article forwardly when said roll is rotated forwardly; and a throat forward to the roll.
- 55 10. In combination, a magazine for a pile of flat articles; a shaft; a pinion fast on said shaft; a reciprocatory link slidingly received on said shaft and having a rack engaging said pinion; a rotary feed roll at the 60 discharge end of the magazine; a throat at said forward end; and a pawl and ratchet connection between said roll and pawl whereby an intermittent forward rotation is given the roll.
- 65 11. In combination, a magazine for a pile of flat articles; a short shaft; a pinion fast on said short shaft; a collar loosely received on said shaft against the said pinion; a reciprocatory link provided with longitudinal slot slidingly received on said collar and 70 provided with a rack engaging said pinion; a ratchet wheel fast on said shaft; a drive plate loosely received on said shaft against said ratchet; a pawl pivotally mounted on said plate and yieldably engaging said 75 ratchet; a rotary feed roll connected to said plate at the discharge end of the magazine bracket; and a throat forward of the roll.
12. In combination, a magazine for a pile of flat articles; a head bracket and a tail 80 bracket at the discharge end of the magazine and provided at the upper part with alined bearing openings; a short shaft in said opening of the head bracket and having a head on its inner end; a pinion fast on 85 said short shaft near the outer end; a collar loosely received on said shaft against the outer face of said pinion; a reciprocatory link provided with longitudinal slot slidingly received on said collar; a rack on said 90 link and engaging said pinion; a ratchet fast on said shaft near the inner end thereof; a drive face plate loosely received on said shaft against said ratchet; a pawl pivotally mounted on the outer face of said 95 drive face plate and yieldably engaging said ratchet, whereby an intermittent forward rotation is given said face plate; a rotary feed roll supported between said face plate and said tail bracket; and a throat forward 100 of the roll.
13. In combination, a magazine comprising side members to engage the side edges of flat articles disposed in a pile therebetween; and a longitudinally adjustable rear 105 support adapted to engage the rear of the articles; and a feed means for said articles.
14. In combination, a magazine comprising a horizontally disposed supporting bracket comprising a main bar; an upright 110 bracket adjustably clamped on the rear part of said main bar; a rear support adjustably secured on the inner face of said upright bracket and formed with a hump to engage articles near the bottom of said pile in 115 said magazine; at the forward end of said magazine and adapted to a feed means and a throat at the forward end of said pile.
15. In combination, a frame; a magazine comprising a horizontally disposed supporting bracket supported on said frame and comprising a rearwardly pointing main bar; upright members carried on the forward ends of said bracket adapted to engage the 120 side edges of flat articles disposed in a pile 125 therebetween; an upright bracket adjustably clamped on the rear part of said main bar; a side block adjustably secured on the inner face of said upright bracket; a rear support secured to the inner face of said block and 130.

- having its lower part formed with a hump to engage the articles near the bottom of said pile; an intermittently rotary feed roll at the forward end of said magazine and 5 adapted to support the forward end of said pile; and a throat forward of the roll.
16. In combination, a horizontally disposed T-shaped supporting bracket supported at its joining portion on said frame 10 and comprising cross bars and a rearwardly pointing main bar; a pair of approximately parallel horizontal side supports each comprising, forward and rear arms and a boss resting on and adjustably secured on the cross bars; upright forward and rear side fingers carried on the respective ends of said arms and adapted to engage the side edges of the flat articles disposed in a pile therebetween; an upright 15 support mounted on the rear part of said main bar; a feed means and a throat at the forward end of said articles.
17. In combination, a horizontally disposed T-shaped supporting bracket supported at its joining portion on said frame 20 and comprising cross bars and a rearwardly pointing main bar; upright forward and rear side fingers carried on the respective ends of said cross bars; and adapted to engage flat articles disposed in a pile therebetween; an upright support on the rear part of said main bar; a feed means and a 25 throat at the forward end of said articles.
18. In combination, a frame; a horizontally disposed T-shaped supporting bracket 30 supported at its joining portion on said frame and comprising cross bars and a rearwardly pointing main bar; a pair of approximately parallel horizontal side supports each comprising, forward and rear arms and a boss resting on and adjustably secured on the cross bars; upright forward and rear side fingers carried on the respective ends of said arms and adapted to 35 engage the side edges of the flat articles disposed in a pile therebetween; an upright support mounted on the rear part of said main bar; a feed means at the forward end of said T-shaped bracket; and a throat forwardly of the feed means.
19. In combination, a magazine for articles; and a feed means for said articles; said feed means and magazine being, except near the forward end, substantially free of 40 parts in engagement with the face or rear edge of said last fed articles just before the commencement of the feeding operation.
20. In a magazine for flat articles, a feed means for said articles; and means whereby the middle, rear and intermediate parts of the last fed articles are free of engagement with the other articles and any rear or intermediate part of the feed means and magazine at the commencement of the 45 feeding operation.
21. In a magazine for articles, a feed means for said articles; and a support for some of said articles; said feed means and magazine being, except near the forward end of the articles, substantially free of 50 parts in engagement with the last fed articles at the commencement of the feeding operation.
22. In a magazine for flat articles, a feed means for said articles; and a support for 55 the rear of some of said articles and from which support the last fed articles are drawn; said feed means and magazine being, except near the forward end, substantially free of parts in engagement with said last fed articles at the commencement of the feeding operation.
23. In a magazine for holding a pile of flat articles, a feed means near the forward end of said magazine; and a support for 60 the rear of said articles and from which the last fed articles are drawn; said feed means and magazine being free of parts in engagement with the mid part of the exposed face of the last fed article just before the commencement of the feeding operation.
24. In combination, a magazine for a pile of flat articles, a rear support below which the rear of the lowest articles may fall when they are drawn forwardly; and a feed 65 means for said articles; the rear, middle and intermediate parts of the article being free of engagement with any part of the feed means and magazine just before its ejection.
25. In a magazine for holding articles, a feed means near the forward end of said magazine; and a support for the rear of 70 said articles and from which lowest article will normally disengage before it commences to be fed; said magazine being, at or before the commencement of the feeding operation of the last article, free of parts in engagement with the exposed face of said last article except at the feed means.
26. In a magazine for holding a pile of flat articles, a feed means at the forward end of said magazine; a throat device through 75 which the articles are fed by said means; and a support for the rear edge of said articles below which the rear edge of the lowest article may fall before the commencement of its ejection, thereby spacing the rear, middle and intermediate parts of said lowest articles from the pile; said throat device being far enough from said support and formed to permit only the lowest articles to fall below the support and to hold the intermediate articles against the support from thus falling; said feed means and magazine being free of parts engaging the rear, middle and intermediate parts of the lowest articles, just before its ejection.
27. In a magazine, a shaft; a rotary member on said shaft; a reciprocatory member 80

having a slot slidably receiving said shaft and rotating said rotary member; and a connection between said member and shaft whereby an intermittent forward rotation is given to the shaft.

28. In combination, a shaft; a reciprocating member slidably and pivotally receiving said shaft; and a connection between said shaft and member whereby an intermittent rotation in one direction only is given to the shaft.

29. In combination, a rotary member; a reciprocating drive member slidably and pivotally received on said rotary member;

and a connection between said members whereby an intermittent rotation is given to the rotary member.

30. In a magazine, a shaft; a pinion on said shaft; a reciprocating member having a slot slidably receiving said shaft and a rack engaging said pinion; and a connection between said pinion and shaft whereby an intermittent forward rotation is given to the shaft.

CHARLES L. LOVERCHECK.
